TELEGRAPH KEY

Murray G. Crosby, Riverhead, N. Y., assignor to
 Radio Corporation of America, a corporation
 of Delaware

Application September 30, 1938, Serial No. 232,498

1 Claim. (Cl. 173—101)

This invention relates to a new and novel pneumatic telegraph key or other type of control key which may be inserted in the mouth of a human being and operated by pressure from the lungs and mouth cavities.

An object of this invention is to simplify and improve a telegraph key of the pneumatic type.

Another object of this invention is to provide a new and novel control key which gives freedom of movement of the hands for other operations, and also allows control of circuits by persons who have lost the use of one or more limbs.

A feature of this invention is the novel arrangement of a fluid chamber having a membrane enclosing a portion thereof with contact means adjacent the membrane whereby the device is actuated by pressure within the chamber from the lungs and mouth cavities of a human being and has the general appearance of that of an ordinary smoker's pipe.

I have found out through my close contact and experience with communication telegraph operators that a control key of my invention makes possible a smoother operation of telegraph sending than is possible by the ordinary type of hand key. Also, the speed of control of a key of my invention is greater than that of the ordinary telegraph key. This smoothness and quickness of control is made possible by the fact that the switching is controlled by the movement of the human tongue which may be actuated at a rapid rate.

This invention will best be understood by referring to the accompanying drawing, in which:

35 Fig. 1 is an elevation of my improved key;
 Fig. 2 is an end view of Fig. 1;
 Fig. 3 is an elevation of another embodiment of this invention;

40 Fig. 4 is an end view of Fig. 3; and
 Fig. 5 is a section similar to Figs. 1 and 2, showing another modification for actuating the diaphragm by means of a piston.

Referring now in detail to the drawing, Figs. 1 and 2 show a key of this invention which is similar to an ordinary smoking pipe and comprises a mouth piece 1 and stem 2 having an air passage 3, which is in fluid communication with a bowl 4 having an air chamber 5 over which is stretched a thin flexible membrane or diaphragm 6, and preferably consists of any suitable material, such as a balloon rubber, leather or the like. Membrane 6 is secured in place by a thin clamp ring 6a. Contact 8 is cemented to membrane

6 and connected by means of a flexible lead 7 to a terminal stud 10 which is provided with a binding nut 12 and is supported out from the end of bowl 4 by means of stud 10 and suitable insulating washers 20 and 21. A metallic contact or 5 arm 9 has a contact member mounted on its underside facing contact 8. The end of member 9 substantially near its point of support is provided with terminal lugs 11 which provide electrical connection to an external circuit which 10 the device of this invention is to control. Member 9 is insulated from stud 10 by insulating washers 20 and 21.

Figs. 3 and 4 show another embodiment which uses a stem and chamber made for the same 15 purpose but not following the shape of the device shown by Fig. 1 and comprises a mouth piece 101, a stem 102 having a passage 103 connecting to an air chamber 105 in bowl 104. Contact 108 is cemented to member 106 and is connected 20 to a metallic support arm 110 by means of a flexible lead 107. A metallic strip 109 has the other contact mounted upon it and is secured to bowl 104 by means of a mounting which comprises an insulating bushing 114, washers 115, 25 nut 116 and terminal stud 117.

The other embodiment shown by Fig. 5 is generally similar to that of Figs. 1 and 2, except for the alternative arrangement wherein contact 9 is secured to a cover or a metallic cross 30 member 6. A piston 20 has contact 8 mounted on it which is connected to binding post 25 through spring 22. Gasket 28 makes the piston air-tight and stops 29 provide a resting position when the key is "off." Connection is made to 35 cross member 6 and contact 9 by means of binding post assembly 26.

While only a few embodiments of this improved control key are shown, it is to be distinctly understood that this invention should 40 not be limited to the precise devices indicated.

What is claimed is:

A contact making device comprising a fluid chamber, a membrane enclosing a portion of said chamber and responsive to pressure within said chamber, a stem having fluid communication with said chamber, the diameter of said chamber being considerably greater than that of said stem, and contact means adjacent said membrane and adapted to be engaged thereby when 50 pressure is applied to said stem.

MURRAY G. CROSBY.
